UNITED STATES PATENT OFFICE.

JOHN SCHEBORA, OF CHICAGO, ILLINOIS.

WINDOW AND FRAME THEREFOR.

1,109,253.

Specification of Letters Patent.

Patented Sept. 1, 1914.

Application filed September 3, 1912. Serial No. 718,239.

To all whom it may concern:

Be it known that I, JOHN SCHEBORA, a citizen of the United States, and a resident of the city of Chicago, in the county of Cook and State of Illinois, have invented certain new and useful Improvements in Windows and Frames Therefor; and I do hereby declare that the following is a full, clear, and exact description of the same, reference being had to the accompanying drawings, and to the numbers of reference marked thereon, which form a part of this specification.

The object of this invention is to afford a window frame and sash construction where-
15 by the two oppositely slideable sashes of the window may both be swung inwardly and downwardly from the frame, although not released therefrom, thereby permitting the window to be thoroughly washed from in-
20 side the room, or permitting repairs to be effected without the necessity of removing and detaching the window from the frame or for operating at the outside the window.

It is an important object of the invention
25 to afford a construction whereby unusual se-
curity for the guides or stops are afforded to
permit the sashes to slide freely and truly
therein, and also to afford a construction
30 whereby the window sashes may be turned
downwardly and inwardly of the room and
held against the draft of the weights while
operated upon.

The invention embraces many novel fea-
35 tures and in its preferred form illustrated
in the drawings, is hereinafter more fully
described.

In the drawings: Figure 1 is an inner face
view of a construction embodying my inven-
40 tion. Fig. 2 is an enlarged, fragmentary,
central vertical section thereof. Fig. 3 is an
enlarged, transverse section, with one of the
sashes shifted to partly open the window.
Fig. 4 is an enlarged, fragmentary, vertical
45 section similar to Fig. 2, but with the lower
sash swung inwardly. Fig. 5 is a similar
view with both the lower and upper sash
swung inwardly. Fig. 6 is an enlarged,
fragmentary detail illustrating the means
50 for engaging one end of the inner stops in
place. Fig. 7 is an enlarged, fragmentary,
sectional detail of the latch for the parting
stop. Fig. 8 is a fragmentary, isometric de-

tail and section, showing the upper sash
swung inwardly and locked to the blind stop.

As shown in the drawings: 1, indicates
55 the side jamb of the window frame; 2, the
inner side casings; and 3, the outer casings
or blind stops. As shown, the jambs are
plowed to receive the usual parting strips 4,
between which and the blind stop the outer
60 upper sash A, slides, and is also plowed
near the inner edge thereof to receive a suit-
able tongue 5, on the inner window stop 6,
between which and the parting strip 4, the
inner or lower sash B, slides.

Weighted sashes are shown. Each of the
sashes is rabbeted longitudinally of each side
rail at the rear or outer corner thereof for
nearly the entire length thereof from the
bottom, so that the sash cords 7 and 8, pass-
65 ing over their respective pulleys, lie closely
adjacent respectively to the inner face of the
blind stop and said parting strip, and are
respectively engaged to the sash to be sup-
70 ported thereon near the bottom of said sash.

As shown, a metallic side plate 9, is re-
cessed into the jamb side or edge of the side
rail for the upper sash A, near the bottom
thereof, and is flanged over into the recess
for the sash cord, as shown in Fig. 8, and
75 provided with an upwardly tapering slot
therein adapted to receive the knotted or
otherwise enlarged end of the upper sash
cord 7. As shown also, said plate 9, is ex-
tended below the bottom of the sash, as indi-
80 cated in Figs. 4, 5, and 8, affording an out-
wardly directed finger or hook 10^a, adapted
to engage in a suitable recess in the blind
stop 3, and beneath a stop plate 10, as shown
85 in Fig. 8, and in dotted lines in Figs. 2, 4,
and 5, and positioned near the bottom of the
frame.

Each of the parting strips engaged on the
side jambs is constructed in two parts, the
upper part extending from the head jamb
90 downwardly for nearly the length of the
upper sash, and provided with a latch com-
bining a slotted plate 11, engaged on the
lower end of said upper parting strip sec-
tion, and slotted longitudinally of, and over
95 the parting strip and having engaged there-
beneath a sliding bolt 12, provided with an
outwardly directed finger piece 13, whereby
the same may be actuated. The lower sec-

tion 14, of the parting strip is shaped at its upper end to fit in the groove therefor and to abut against the lower end of the upper section 3, and is engaged in place by the 5 tongue or bolt 12, fitting thereover and in a suitable recess in the upper end thereof provided therefor. The lower end of said parting strip extends into a suitable recess in the 10 sill to insure the same being held rigidly in place.

The stop for the lower sash is similarly constructed in two sections, the upper section 6, thereof having secured on the lower end thereof an ornamental block or enlargement recessed on the under side in register with the groove for the tongue 5, and into which extends the end of the tongue for the lower stop section 15, as shown in dotted lines in Figs. 4 and 5. As shown, said lower 15 stop section 15, is provided with an ornamental or other button 16, near the lower end, and projecting from the face thereof and engaged in the lower end of said stop to bear upon a suitable friction member on 20 the sub-sill 18, is a friction latch 17, acting to hold said stop firmly in place normally. As shown, the groove in the jamb for said 25 tongue 5, is slightly enlarged near the bottom of the jamb, and a rearwardly opening 30 hook 19, is engaged in the jamb therein to receive the sash cord, as shown in Fig. 4. The jamb is also cut or slightly slotted 35 obliquely just below the lower end of the upper stop section 6, and a plate 20, pivotally engaged on the jamb and set flush with the outer face thereof, is adapted to be 40 swung outwardly, as shown in Fig. 4, across the groove in the jamb to engage the sash cord when the lower sash is swung outwardly.

The operation is as follows: The respective sashes under normal condition, are movable as all such sashes are, in opening and closing the window, the upper sash being 45 movable downwardly and the lower sash upwardly, and, of course, any desired number of sashes may be provided one above the other, providing sufficient guideways are provided therefor. When it is desired to 50 swing the lower sash inwardly, the lower stop sections 15, are removed by pulling on the button 16, overcoming the frictional resistance of the friction latch 17. The stops being removed from the frame, the top of 55 the lower sash may be engaged and pulled outwardly to sufficiently expose the sash cord which is first engaged in the oblique slot therefor, and then pressed into the groove and held in place by the swinging 60 plate 20, which projects across the groove, as shown in Figs. 4 and 5. The sash is then swung downwardly, as shown in Fig. 4, and the sash cord engaged behind the hook 19.

The lower sash is now held from raising by engagement of the cord on said hook and 65 requires no further attention, the line being cramped on the pulley and at its entry in the groove in the jamb and bound in place by the latch plate 20, sufficient resistance is afforded to overcome the gravity of the 70 weights on the cord. Of course, the top end of the sash may be supported upon any suitable article of furniture or otherwise to prevent the same tilting down unduly. The upper sash may now be drawn downwardly, 75 the latch plate 12, retracted to release the upper end of the parting strip section 14, and the same may then be removed from the jambs, after which the top of the said sash is pulled forwardly, such forward swing of 80 the sash acting to immediately engage the hook 10^a, beneath the plate 10, secured on the blind stop, as shown in Fig. 8, and in dotted lines in Fig. 5, so that the sash may be 85 swung down to rest flat upon the lower sash, the draft of the sash cord being applied to 90 said sash near said hook 10^a, being insufficient to swing the sash upwardly and again in the frame. Having washed, repaired, inspected or otherwise performed the labor for 95 which the sashes were swung into the room, they may be quickly restored to their normal and usual position by merely swinging the upper sash A, back into the frame, which automatically releases the hook 10^a, permitting the sash to rise under the influence of 100 its weights to the position shown in Fig. 4. The lower section of the parting strip may now be returned and secured in place, whereupon the lower sash B, may be swung into 105 position, the sash cords being first detached from the hooks 19, the plates 20, swung outwardly to clear the sash cord, and the sash cord permitted to snap back to normal position as the sash is replaced in the frame. 110 The lower stop sections 15, are then restored to position by engaging the projecting end of the tongue 5, at the upper end of said lower stop in the recess therefor and pressing the stop into place to engage the friction 115 latch, as before described. The sash is now in all respects restored to operative position.

I have shown and described but a preferred construction embodying my invention, although, of course, I am well aware 115 that many details of construction and operation may be varied. I therefore do not propose limiting myself otherwise than necessitated by the prior art.

I claim as my invention:

The combination with a sliding sash, and a frame therefor, of rope attaching and locking means comprising a metallic plate attached to the side rail of the sash and having a portion thereof bent at an angle thereto 125 and provided with a tapered slot to receive

the knotted end of a rope for supporting the sash, said side plate being extended into a projecting hook formed integrally therewith, and a plate projecting partly over a recess in the frame adapted to be engaged by said hook when the sash is rotated in a horizontal position to prevent removal of the sash from the frame.

In testimony whereof I have hereunto subscribed my name in the presence of two subscribing witnesses.

JOHN SCHEBORA.
